UNITED STATES PATENT OFFICE.

ZENO M. SPEER, OF WAUWATOSA, WISCONSIN, ASSIGNOR TO SPEER-ROSEFELT CALENDAR BANK, INCORPORATED, OF MILWAUKEE, WISCONSIN, A CORPORATION OF WISCONSIN.

BANK.

Application filed August 23, 1920. Serial No. 405,291.

To all whom it may concern:

Be it known that I, ZENO M. SPEER, a citizen of the United States, residing at Wauwatosa, in the county of Milwaukee and 5 State of Wisconsin, have invented a certain new and useful Improvement in Banks, of which the following is a full, clear, concise, and exact description, reference being had to the accompanying drawings, forming a 10 part of this specification.

My invention relates to calendar banks, or more specifically described, to savings banks in which is employed a coin controlled perpetual calendar which may be advanced 15 daily by the insertion of appropriate coins. The particular purpose of the device is to stimulate the habit of regular and systematic saving.

One of the principal objects of the invention is to devise a construction of calendar bank of the fewest and simplest parts, capable of being made and assembled at minimum cost. The calendar type of bank has a particular field of utility as a savings bank 25 adapted for distribution by banking institutions to their savings depositors. To fulfill the requirements of this use, it is primarily essential that the bank be of extremely low cost, so as to induce the adoption 30 of the bank for distribution by the banking institutions, and to this end I have devised an extremely simple construction which is capable of production at a relatively low cost.

With this in view, a further object of the invention has been to provide a form of advancing mechanism for the calendar element wherein the coin itself is made to function as the advancing instrumentality by arranging the coin to engage directly with the calendar wheel so as to move bodily with the calendar wheel through its advancing throw. Heretofore, the general practice has been to advance the calendar wheel 45 through the intervention of complicated pawl and ratchet mechanism or the like which was actuated or controlled by the coin. The necessity for this complication has been entirely eliminated by the present 50 construction.

A further object of the invention is to provide a simplified and positive form of integrating or advancing mechanism for automatically advancing the months wheel

at the proper calendar period in the operation of the bank. 55

Referring to the accompanying drawings wherein I have illustrated a preferred embodiment of my invention;

Figure 1 is a front elevational view of 60 a calendar bank embodying my invention;

Figure 2 is a vertical sectional view through the casing of the bank;

Figure 3 is a plan view of the bank;

Figure 4 is a horizontal sectional view 65 taken on the plane of the line 4-4 of Figure 1; and

Figure 5 is a detail sectional view taken on the plane of the line 5-5 of Figure 2.

The calendar bank mechanism is enclosed 70 in a sheet metal housing 63 which engages down over a removable bottom plate 64 having enclosed end walls 65 and 66. The front of the housing 63 is provided with two sight openings 67 and 68 through which 75 are exposed the legends on the days and months wheels. The top wall of the housing 63 is provided with the usual coin slots 69 and 71 for the insertion of coins into the bank, the former slot 69 being the slot 80 through which coins for advancing the calendar are inserted. In this embodiment, the calendar wheels are constructed as discs 72 and 73, the large disc 72 having the numerals corresponding to the days of the 85 month inscribed on the face thereof and the small disc 73 having the names of the months marked off radially thereon. Both discs are supported in close proximity to the front 90 wall of the housing 63 upon shafts 74 and 75 which are supported in a vertical partition or wall 76 which extends between the end plates 65 and 66 of the removable bottom 64. The ends of the partition plates 76 are flanged to fasten to the vertical inner walls 65 and 66, and the partition plate 76 extends from the bottom plate 64 to the height indicated in Figure 11 for the purpose of defining a spacious coin compartment to the rear of the plate 76, as indicated 95 at 78. As a result of this construction, the removable of the bottom plate 64 will carry with it the partition plate 76 and the calendar wheels 72 and 73 supported thereon, and will discharge the coins from the coin compartment 78. Any suitable form of lock 100 may, of course, be provided for locking this removable bottom in the housing 63. It

will be noted that by the use of discs as indicating wheels and by disposing these discs in the same plane a very narrow, compact construction is obtained.

- 5 The days indicating wheel 72 has its periphery formed with a plurality of scalloped indentations 79 corresponding to the number of days in the longest month, these scalloped indentations being struck on arcs 10 of substantially the same radius as that of the coin for advancing the calendar bank. The coin slot 69 is aligned directly above the days wheel 72 and adjacent one end of the housing 63. To advance the calendar, 15 a coin is inserted through the slot 69 whereupon it automatically seats along its periphery in one of the scalloped indentations 79. The coin is thence thrust downward diagonally by pressing the same with 20 the thumb or finger until the coin passes below the margin of the slot 69 into the position indicated in full lines. At the completion of this downward thrusting motion of the coin, the coin has functioned to advance the days wheel 72 through one step. 25 When the coin reaches approximately the position indicated in full lines, it is ejected laterally from the indentation 79 and is discharged over into the coin compartment 78. 30 This ejection of the coin from the calendar disc is accomplished by a short leaf spring 80 (Figure 5) which is secured at its upper end to the front wall of the housing 63 and which at its lower resilient end projects into 35 the path of the coins. As the coin is depressed through the slot 69 in performing the advancing operation, it meets the increasing lateral tension of the spring 80 which tends to eject the coins laterally from 40 the disc 72 and discharge them into the coin compartment 78. As long as the upper portion of the coin is confined between the sides of the slot 69 and as long as the coin is firmly pressed against the calendar disc 45 72, the ejecting spring 80 is of no avail for ejecting the coin from the disc. As soon, however, as the coin passes below the upper margin of the coin slot 69 and as soon as the depressing tension on the coin is released 50 by the coin passing beyond the influence of the depressing finger, the ejecting spring 80 immediately becomes effective for ejecting the coin and clearing the coin passage for the next succeeding coin. By reason of the 55 inability of the spring 80 to eject the coin until it reaches such position, it is always as-

sured that the coin will impart a full advancing step to the calendar disc before it can be ejected therefrom. The disc 72 is retained in its exact indicating position 60 after each advancing step by a detent spring 82 which is secured to the bottom plate 64 and which engages in the scalloped periphery of the disc. A flange or shelf 83 may be bent over from the partition plate 65 76 at the end of the coin passage to limit the downward motion of the coins and to prevent any of the coins from accidentally entering the calendar wheel space between the front wall of the housing and the partition plate 76.

The carry-over operation between the calendar discs 72 and 73 is performed by a projecting pin 84 on the rear of the disc 72 which is adapted to engage with a series 75 of pins 85 projecting from the rear of the months disc 73. The pin 84 is located directly in rear of the numeral 31 on the days disc 72, so that it will be timed to engage the cooperating pin 85 on the disc 73 and 80 advance the latter at the same time that the numeral 1 is presented at the sight opening 67. The months disc 73 is accurately maintained in its various indicating positions by a detent spring 87 which is secured to 85 the bottom wall 64 and which engages at its upper end between the pins 85.

I do not intend to be limited to the particular details herein shown and described, except as they are specifically defined in the 90 appended claim.

I claim:

In a device of the class described, in combination, a casing, a wall subdividing a relatively narrow compartment along one face, 95 a slot in the casing aligned with said compartment, a registering wheel in said compartment positioned for direct engagement with the edge of an inserted coin, a second slot opening over the other portion of the 100 casing, resilient means engaging a coin inserted through said first slot and tensioned by insertion thereof for deflecting said coin laterally into the portion of the casing under said second slot, and a biasing spring 105 for said registering wheel whereby the load on the coin is suddenly released to permit said deflecting means to act.

In witness whereof I hereunto subscribe my name this 19th day of August, 1920.

ZENO M. SPEER.
